David Miller Patented Massachusetts

Setting Patent

The Schedule of parts to be used in these Settling Patent and making part of the accompanying description in the words of the said David Miller have
left off his improvement in Patent Office.

To all to whom these presents shall come, G. David Miller of the
City of Boston in the County of Suffolk a citizen of the Commonwealth
of Massachusetts hereby certifying, That it is known that the said
Miller have made and applied to use a new and useful
improvement in Settling traps which invention and improvement
has never been known or used before and which I do now and certify
as follows. That is to say figures numbered respectively one two three
four five and six which are annexed as a part of this specification, as
also a sketch of the front view of the trap with the new invention and improve-
ment. The parts A B C, in the several figures are to be made of
leather cloth or such material as of leather or traps are made
by me. Each figure is intended to represent half of an entire
trap. The other half is to be made to correspond with that represented
in the figure. The traps may be made in pieces or in
as represented in the figures or made in several pieces as is
represented in the other figures. When made of one entire piece they
may be fastened to the partitions by loops 6 8 or 10 as represented in
said figures numbered one, and when in several pieces or pieces by
loops 6 8 as is represented in the other figures. or in any
other convenient way. A small spring of steel or other metal
as is represented in the several figures is used, though about
the same may be used. The parts A B C are to be made of
leather cloth or such material as of leather or traps are made
by me. The parts A B C are to be made of leather cloth or
such material as of leather or traps are made by me.

In order to secure safety, the ends of the strings of cat gut are to be
twisted to the ends of the spiral springs. The spiral springs are to be
placed in a case formed of leather, and covering leather cloth or like
material, with a cap over the springs, so as to protect them in the usual
fashion of the United States. The spiral springs are to be fastened to the ends
of the case and prevented from being drawn out from the case on
which they are to be enclosed, while the strings of cat gut or other like
material are drawn which strings are to be allowed to make one by
half and fourteenths in the spiral spring. The advantage of this spring will
be in this manner to facilitate the ship to go to general service, so that
the amount may great, and when this is upon the ship to be ready, will be
very easily repaired. The springs may be all made with strings
of cat gut or other suitable material passing through and winding
in them in any other convenient way. The spring appears being ordered
to be in this or some of the most eligible way, of all reducing the same
to the proportions. That no invention connects with the protection
of spiral springs with cat gut strings or other material as fore
and passing them through and winding on them as aforesaid, to pro
tect them for the purpose aforesaid.

Witness of that the above is a true representation of my invention
above named. I have hereat set my hand this nineteenth day of Au
gust in the year of our Lord Eighteen hundred and thirty three
